UNITED STATES PATENT OFFICE.

WILLIAM GRAY, OF AMESBURY, MASSACHUSETTS.

DESIGN FOR A VEHICLE-LAMP.

SPECIFICATION forming part of Design No. 34,753, dated July 9, 1901.

Application filed June 11, 1901. Serial No. 64,179. Term of patent 3½ years.

To all whom it may concern:

Be it known that I, WILLIAM GRAY, a citizen of the United States, residing at Amesbury, in the county of Essex and State of Massachusetts, have invented and produced a new and original Design for a Vehicle-Lamp; and I do hereby declare the following to be a full, clear, and exact description of the same, reference being had to the accompanying drawings, forming a part thereof.

Figure 1 is a front view, Fig. 2 is a side view, and Fig. 3 is a rear view, of a vehicle-lamp, showing my new design.

As shown in the drawings, the leading or material feature of my design consists of a cylindrical lamp-body A, having top and bottom panels B C, such panels having, respectively, flat upper and lower surfaces and semicylindrical ends b b c c. Below the panel C is the stem, having an upper convex portion E and a lower concave portion F, terminating as a head f and flat bottom f', as shown. Above the panel B is the head, having a concave neck G, terminating as a convex upper head-cap H, as shown.

I is the bail, curved and conforming substantially to the shape of the head.

In front of the cylindrical body A is a cylindrical flange K, and k is a convex glass at the end of the said cylindrical flange K, as shown.

On one side of the body A is a convex glass L, conforming to the curvature of the said body A. At the rear of the body is a beaded cylindrical back M, terminating as a convex rear end or cover m, as shown in Figs. 2 and 3.

Having described my invention, what I claim as new, and desire to secure by Letters Patent, is—

The design for a vehicle-lamp, as herein shown and described.

In testimony whereof I have affixed my signature in presence of two witnesses.

WILLIAM GRAY.
